JAMES JAQUES VERRETTE AND ALEXANDER W. WHITE, OF ODANAH, WISCONSIN.

TIMBER-TONGS.

1,307,887.

Specification of Letters Patent. Patented June 24, 1919.

Application filed October 24, 1918. Serial No. 259,473.

To all whom it may concern:

Be it known that we, JAMES J. VERRETTE, and ALEXANDER W. WHITE, subjects of the Kingdom of Great Britain, residing at 5 Odanah, in the county of Ashland and State of Wisconsin, have invented certain new and useful Improvements in Timber-Tongs; and we do hereby declare the following to be a full, clear, and exact description of the 10 invention, such as will enable others skilled in the art to which it appertains to make and use the same.

This invention relates to timber tongs and particularly to a construction whereby the 15 tongs are provided with a swivel connection with a cable or other supporting device.

The invention has for an object to provide a novel and improved construction of tongs 20 wherein the angular sliding lever is provided with a bifurcated head to embrace the angle ends of the tongs jaws, together with a curved yoke having a central aperture and pivoting ears at opposite ends for the tongs 25 jaws.

Another and further object of the invention is to provide an improved construction of the swivel connection comprising a head adapted to be threaded upon the end of the 30 tongs lever and carrying an eye loosely swiveled therein.

Other and further objects and advantages of the invention will be hereinafter set forth and the novel features thereof defined by 35 the appended claim.

In the drawing:

Figure 1 is an elevation of the tongs with a portion of the yoke and lever in section;

Fig. 2 is a detail perspective of the operating lever; and

Fig. 3 a bottom plan of the yoke.

Like numerals refer to like parts in the several figures of the drawings.

The numeral 10 designates the yoke of the 45 tongs which is preferably formed of curved construction so that the depending ends 11 thereof are provided with a slot 12 thus forming pivot ears for the jaws 13 of the tongs. These jaws may be of any desired 50 size or configuration and are pivoted within the slot 12 of the yoke ends by means of the cross bolts 14 extending between the side walls of the slot. The upper end 15 of each of the jaws 13 is disposed at an angle to the 55 remainder of the jaw and formed with a slot 16 at its free end 17.

The yoke is centrally provided with an angular aperture 18 which acts as a guide for the stem 19 which is of angular cross section and is thus prevented from turning 60 and guided in a straight path. The lower end of this stem is formed with a head 20 provided with a cross slot 21 into which the ends 17 of the upper portion of the jaws extend. The jaw ends are connected with the 65 head by cross pins 21 extending between the walls of the slotted head. The upper face of this head is curved as at 23 and seats against the under face of the yoke adjacent the aperture 18 therein so as to limit the inward movement of the jaws toward each other in their closing movement. The angularly disposed ends 15 of the jaws also 70 abut against the inner wall 24 of the slot 22 so that when the points 25 of the tongs 75 are firmly embedded in the timber or other material and the strain is applied to the stem, these parts are braced both at the center and the ends of the yoke so that there is practically no danger of slipping or yielding 80 under the lifting strain. For the purpose of providing a swivel connection for the tongs particularly when a hauling or supporting cable is used as in timber transportation, a swivel head 26 is provided. 85 The lower portion of this head is formed with a threaded aperture 27 to receive the threaded end 28 from the angular body 19 of the stem and if it be desired to lock these parts in their assembled relation a key 29 90 may be inserted through an aperture in the head and a corresponding aperture 30 in the threaded end 28. This head is also provided with a central opening 31 adapted to receive the head 32 carried by the shank 95 33 of an eye-bolt 34 through which a cable is adapted to be passed. The shank 33 of the eye-bolt extends through an opening 35 in the head so as to provide a swivel or 100 pivotal connection at that point by which the tongs may be swung in a rotary path or to any degree thereof necessary to permit the material carried thereby to pass other objects and also to prevent the cable from twisting or kinking as it is free to move 105 through the eye which adjusts itself in position.

The operation of the invention will be apparent from the foregoing description from which it will be seen that the tongs are 110 particularly adapted in timber or shipbuilding work and owing to their braced

construction are not liable to slip when engaged with material. The tongs are also very powerful because the four pivotal centers are in substantially the same transverse line and receive the same strain on each when a load is being carried by the tongs. It will also be noticed that the curved form of the yoke causes it to form practically a continuation of the jaw from its pivot upward to the point where the head of the stem has its bearing on the underface of the yoke. This causes the lifting strain of the jaws to be carried practically from the head of the stem, which in its movement also actuates the swinging of the jaws.

It will be seen that the invention comprises a simple, efficient and very economical construction of tongs and one in which the swivel connection may be removed from the slide lever and replaced by any other desired attachment for handling the tongs.

What we claim is:—

Tongs embodying a curved yoke having a central angular aperture, jaws pivoted to the ends of the yoke and having portions 25 extending at an angle within the yoke, a stem of angular cross section sliding through said aperture and having a head within the yoke curved to fit the yoke, said head having a slot and transverse pins extending 30 through the slot, and said portions of the jaws extending within said slot and having slots engaging said pins.

In testimony whereof we have signed our names to this specification in the presence of 35 two subscribing witnesses:

JAMES JAQUES VERRETTE.
ALEXANDER W. WHITE.
